(57) **CLAIM**

The ornamental design for a “wheeled riding device,” as shown and described.

DESCRIPTION

FIG. 1 is a top, front, and right side perspective view showing our new design for a wheeled riding device.

FIG. 2 is a right side view of the wheeled riding device shown in FIG. 1.

FIG. 3 is a top view of the wheeled riding device shown in FIG. 1.

FIG. 4 is a front view of the wheeled riding device shown in FIG. 1.

FIG. 5 is a rear view of the wheeled riding device shown in FIG. 1.

FIG. 6 is a left side view of the wheeled riding device shown in FIG. 1; and,

FIG. 7 is a bottom view of the wheeled riding device shown in FIG. 1.

The subject matter shown in dashed lines are included for the purpose of illustrating the unclaimed portions of the article and form no part of the claimed design.

1 Claim, 7 Drawing Sheets
